W. E. KIMBER.
HAMMER ROCK DRILL.
APPLICATION FILED DEC. 27, 1915.

1,212,141.

Patented Jan. 9, 1917.

By J. G. Somes
Attorney.

UNITED STATES PATENT OFFICE

WALTER E. KIMBER, OF HARLESDEN, LONDON, ENGLAND.

HAMMER ROCK-DRILL.

1,212,141.

Specification of Letters Patent.

Patented Jan. 9, 1917.

Application filed December 27, 1915. Serial No. 68,840.

To all whom it may concern:

Be it known that I, WALTER EDWARD KIMBER, a subject of the King of Great Britain, residing at 37 Inman road, Craven Park, 5 Harlesden, London, England, have invented new and useful Improvements in Hammer Rock-Drills, of which the following is a specification.

The present invention relates to improvements in hammer rock drills and consists in the special arrangement for imparting the desired rotary movement to the bit or tool and also for allowing either water under pressure or compressed air, or a combination 15 of the two, to pass along a hole bored in the bit into the bore hole to allay the dust and remove debris.

The invention enables these objects to be carried into effect in a most simple and efficient manner, the special construction employed for this purpose being illustrated in the accompanying drawings, in which—

Figure 1 is a longitudinal section of the complete drill, and Fig. 2 a similar section, 25 drawn to a larger scale, of the piston or hammer cylinder and the tappet or anvil on which same operates and constituting the chuck carrying the bit or tool.

In these figures 1 is the piston constituting 30 the drill hammer which is mounted to reciprocate in the drill cylinder 2 upon a central rod 3 the opposite ends 4 and 5 of which are made of square or similar section to engage one (4) with the rear end of the chuck 6 the forward end of which receives the stem of the bit or tool 7, while its opposite end (5) engages a rearwardly extending sleeve 8 capable of rotation in relation to the drill cylinder 2 with which it is in axial alinement.

40 The sleeve 8 extends into a tubular part 9 secured by the clamp 10 so as to constitute part of the frame or support of the drill and which in operation remains stationary, while the sleeve 8 and with it the bit or tool 7 is capable of both rotary and longitudinal movement in relation thereto.

The rear end of the tubular part or drill frame 9 has a spindle 11 mounted therein and fitted with a crank 12 by which same 50 can be manipulated by hand, said spindle extending forward and engaging the sleeve 8 (connected with the rear of the drill cylinder 2) in such a way as to cause same to rotate under the action of said crank. The 55 movement imparted to the crank 12 will be transmitted to the sleeve 8 causing same to

rotate within the drill frame 9, and also within the cylinder casing 2 with which its rear end is connected, said movement in turn being transmitted through the rod 3 upon 60 which the hammer piston 1 reciprocates to the bit chuck 6 and so to the bit or tool 7.

The ends of the rod 3 form a slightly loose fit in the recesses in which same engage respectively in the sleeve 8 and the bit chuck 65 6 so as to permit of any necessary slight adjustment to insure alinement and allow of perfect fit and working of the piston hammer 1 on such rod 3, without throwing excessive strain on the parts when exerting the 70 effective stroke upon the rear of the chuck 6 which constitutes the anvil to receive the blow and transmit it to the bit or tool 7 carried in such chuck. The motive fluid connection and the construction of valve for 75 regulating the distribution of such fluid to the piston cylinder may be of any known or approved construction.

The drawing shows a piston valve 13, working in a valve casing consisting of two 80 flanged members 20, 20^a and a tubular member 20^b, the parts being held in correct position relatively to one another and the valve chest by a spring 14; said valve 13 controlling the supply of motive fluid entering at 85 15 to the passages or ports 16, 17, leading respectively to the opposite ends of cylinder 2, in which the piston or hammer 1 is mounted to reciprocate on rod 3, while the cylinder casing 2 is provided with suitably situated 90 exhaust ports 29, 30, which are permanently open to exhaust.

The spindle 11 which extends into the tubular drill frame 9 only engages the rear part of the sleeve 8 which works therein, a 95 clearance 18 being left between such spindle and the interior of the sleeve beyond such point of engagement. This space 18 is through passage 19 permanently open to the pressure of the motive fluid in the valve 100 chest 20, and a passage or leakage 21 allows same to pass to the rear of the tubular drill frame 9. The rear end of the sleeve 8 is provided with packing rings 22 and constitutes a piston working in the tubular frame 105 9, and the pressure of the motive fluid exerted on the rear thereof by forcing said sleeve 8, and with it the drill cylinder casing 2, forward in relation to such tubular frame, will keep the drill 7 to its work.

110 The stem of the bit or tool 7 is provided with a screwed part 23 to engage a corre-

sponding thread in the fore end of the drill 5
chuck 6, and a rearward extension 24 from
said screw engages with and abuts against
the bottom of a socket formed to receive
same in said chuck. The screw thread is to
the hand to insure that the rotation imparted
to the chuck 6, by hand through the spindle 22 and the central connecting rod 3 when
the crank 12 is actuated, will tend to force
10 the bit extension firmly to its seat in the re-
cess it engages.

The compressed air or water under pressure, or both, to be supplied to the bore 25
of the drill 7 for allaying the dust and re-
15 moving the debris from the bore hole is con-
veyed to an annular recess 26 formed in the
part of the casing 2 in which the chuck 6 is
mounted and is capable of rotary and lon-
20 gitudinal movement, and from which an-
nular recess 26 a hole 27 is pierced inward
to the center of the bottom of the socket
which the bit extension 24 engages, so that
said fluid can pass into the central hole 25
formed through the length of the bit and so
25 out through openings at the end thereof into
the bore hole, thereby allaying the dust and
removing the debris therefrom. A squared
part 28 on the drill stem forward of the
30 screwed part 23, by means of a spanner,
permits of the screwing home of the bit to
its seat in the chuck, and its release when
desired to remove the bit.

It will be understood that the special
35 construction of the chuck and the end of
the drill bit as also that for the supply of
liquid or compressed air to the bore hole for
allaying the dust and removing debris
therefrom are not claimed other than in the
40 special construction of drill hereinbefore de-
scribed in which the piston or hammer is
caused to reciprocate on a rod connecting
said chuck with a rearward extension of the
drill cylinder and capable of rotation in re-
lation thereto.

45 What I claim as my invention, and desire
to secure by Letters Patent, is:—

1. In a fluid actuated rock drill, the com-
bination of a supporting cylinder, a rota-
table spindle disposed axially of said cylin-
50 der and provided with rotating means, a

sleeve slidable and rotatable in said sup-
porting cylinder, engaged by said spindle
and having a forward projection beyond
said cylinder, a hammer cylinder mounted on
said forward projection of the sleeve and 55
rotatable thereon, a rotatable bit-carrying
chuck in the forward end of said hammer
cylinder, a central rod disposed within said
hammer cylinder and connecting said chuck
with said sleeve projection, and a piston 60
hammer slidable on said rod within said
hammer cylinder.

2. In a fluid actuated rock drill, the com-
bination of a supporting cylinder, a rota-
table spindle disposed axially of said cylin-
65 der and provided with rotating means, a
sleeve slidable and rotatable in said support-
ing cylinder, engaged by said spindle and
having a forward projection beyond said cyl-
inder, a hammer cylinder mounted on said 70
forward projection of the sleeve and rota-
table thereon, a rotatable bit-carrying chuck
in the forward end of said hammer cylinder,
a central rod disposed within said hammer
cylinder and connecting said chuck with said 75
sleeve projection, a piston hammer slidable
on said rod within said hammer cylinder,
means for supplying a motive fluid to said
hammer cylinder, and means connecting said
supply means with said sleeve. 80

3. In a fluid actuated rock drill, the com-
bination of a hammer cylinder, a rotatable
sleeve connected with the rear end of said
hammer cylinder and provided with an an-
gular socket, a rotatable bit-carrying chuck 85
in the forward end of said hammer cylinder
and provided with an angular socket, a cen-
tral rod having angular opposite ends en-
gaging said sockets with a loose fit which
permits an alining adjustment, and a piston 90
hammer slidable on said rod within said
hammer cylinder.

In testimony whereof I have signed my
name to this specification in the presence of
two subscribing witnesses.

W. E. KIMBER.
